CLAIM

We claim the ornamental design for a digital camera, as shown and described.

DESCRIPTION

FIG. 1 is a front, top, right-side perspective view of a digital camera according to the present invention;

FIG. 2 is a back, bottom, left-side perspective view thereof;

FIG. 3 is a front view thereof;

FIG. 4 is a rear view thereof;

FIG. 5 is a top view thereof;

FIG. 6 is a bottom view thereof;

FIG. 7 is a right-side view thereof;

FIG. 8 is a left-side view thereof;

FIG. 9 is a front, top, right-side perspective view thereof, showing a camera base in broken lines;

FIG. 10 is a back, bottom, left-side perspective view thereof, showing a camera base in broken lines;

FIG. 11 is a right-side view thereof with the digital camera in the first alternate position and showing a camera base broken lines; and,

FIG. 12 is a right-side view thereof with the digital camera in the second alternate position and showing a camera base broken lines.

The broken line showing of the camera base in FIGS. 9-12 is for illustrative purposes only and forms no part of the claimed design.
